FRAME FOR BADMINTON AND TENNIS RACKETS

Charles A. Thompson, New Sharon, Maine

Application December 30, 1938, Serial No. 248,382

1 Claim. (Cl. 273—73)

This invention relates to new and useful improvements in a frame for badminton and tennis rackets.

The invention has for an object the construction of a frame which is characterized by a handle consisting of a plurality of longitudinal sections stacked together and having outwardly flared top portions, a head for the strings or gut mounted on said handle in a specific manner, and wedge shaped throat pieces associated with said handle and head in a certain manner.

More specifically, the invention contemplates to arrange the parts in a manner so that the outwardly flared top portions assist in holding the head in position.

Still further the invention proposes to so arrange the ends that the outwardly flared top portions oppose stresses and strains tending to pull the head of the racket outwards relative to the handle.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is a side elevational view of a racket constructed according to this invention.

Fig. 2 is a fragmentary enlarged sectional view of the central portion of Fig. 1.

Fig. 3 is a horizontal sectional view on the line 3—3 of Fig. 1.

Fig. 4 is a horizontal sectional view taken on the line 4—4 of Fig. 1.

Fig. 5 is a fragmentary view similar to Fig. 2 but illustrating another embodiment of the invention.

Fig. 6 is a side elevational view of a racket constructed according to a still further modified form of the invention.

Fig. 7 is a horizontal sectional view taken on the line 7—7 of Fig. 6.

Fig. 8 is a vertical sectional view taken on the line 8—8 of Fig. 7.

The frame for badminton and tennis rackets, according to this invention, includes a handle 10 consisting of a plurality of longitudinal sections 10^a, 10^b, 10^c stacked together and having outwardly flared portions 11 at the top arranged in a certain manner. A head 12 for the string or gut of the racket is formed from a strip of material arranged in substantially circular configuration and having its ends 12^a and 12^b engaging

the opposite sides of the handle 10. A reinforcement strand 13 is engaged about the handle 10 and the ends 12^a and 12^b for reinforcing these parts.

The section 10^a of the handle constitutes the central section of the handle. The top end of this section is straight. The sections 10^b and 10^c constitute outer sections arranged upon the sides of the central section 10^a. The upper ends of these sections flare outwards to form the outwardly flared portions 11. Wedge shaped throat pieces 14 are engaged in the space between the flared portions 11 and the top of the central section 10^a. Other wedge shaped throat portions 15 are engaged in the spaces between the flared portions 11 and the end portions 12^a and 12^b. A strip of material 16 is arranged around the inner surface of the head 12 to reinforce the same and to prevent the gut from becoming worn at the portions engaging the head 12. Reference numeral 17 indicates the gut mounted on the head 12 in a conventional manner.

The inventive feature may be understood from the following. The ends 12^a and 12^b, the flared portions 11, the wedge shaped throat pieces 14 and 15, and the central section 10^a are all joined together in an integral unit by gluing, cementing, or any other similar method. When the racket is being used it is held by the handle while its head is used to strike a ball. This produces a tendency causing the head to fly relatively outwards from the end of the handle. This tendency is restrained by the outwardly flared top portions 11. In order for the head 12 to fly off it would be necessary that the ends 12^a and 12^b either compress the wedge shaped throat portions 14 and 15 to destruction, which is impossible, or themselves spread over the wedge shaped pieces. This latter condition is also impossible.

In Fig. 5 a modification of the invention has been disclosed which distinguishes from the prior form in the fact that a rivet 18 is engaged through the outwardly flared top portions 11 and the wedge shaped pieces 14. This rivet assists in joining these parts together as a unit and adds to the strength of the construction.

In Figs. 6-8 inclusive another form of the invention has been disclosed which distinguishes from the prior form particularly in the construction of the outwardly flared top portions. In this form of the invention the outwardly flared top portions 11' are each of semi-conical form. The central handle section 10^a is flat. The edges of the semi-conical flared portions rest upon edge portions of the flat central section 10^a. The 55

flared portions 11' are not truly semi-conical in form, but closely simulate a frustum of a cone. Wedge shaped throat pieces 14' are engaged within the flared portions 11'. Other wedge shaped portions 15' are engaged between the outer surfaces of the flared portions 11' and the ends 12^a and 12^b. In other respects this form of the invention is similar to the previous form.

The feature of this form of the invention resides in the fact that the outwardly flared top portions 11' because of their curved formations serve to rigidly and firmly hold the head of the racket.

While I have illustrated and described the preferred embodiments of my invention, it is to be understood that I do not limit myself to the precise constructions herein disclosed and the right is reserved to all changes and modifications coming within the scope of the invention as defined 20 in the appended claim.

Having thus described my invention, what I

claim as new, and desire to secure by United States Letters Patent is:

A frame for tennis rackets and the like comprising a laminated handle portion formed of a plurality of strips of wood stacked together, each 5 of said strips having an upper portion tapered in thickness to provide a tapered neck portion, a head portion comprising a curved strip of material substantially circular in configuration, the inner sides of the last-named strip of material 10 tapering at the ends thereof so as to lie complementary with the tapered neck portion, and a throat portion formed by wedges engaged between the top end portions of the strips forming the handle thereby causing said strips to flare 15 outwardly, and wedges engaged between the outwardly flared ends of the strips and the curved strip forming the head portion, said strips and wedges being secured to one another.

20

CHARLES A. THOMPSON.
